CLAIM

The ornamental design for a cover for an inlet grill on
an air conditioner, as shown and described.

DESCRIPTION

FIG. 1 is a prospective view of a cover for an inlet grill
on an air conditioner showing my new design;
FIG. 2 is a top plan view thereof;

FIG. 3 is a side elevational view thereof;

FIG. 4 is a bottom plan view thereof; and

FIG. 5 is a front elevational view thereof.
The fragmentary broken line representation of an air
conditioner in FIG. 1 is for purposes of illustration only.
